A. GUENTHNER.

PLOWSHARE,

APPLICATION FILED JULY 28, 1919.

1,410,403.

Patented Mar. 21, 1922.

UNITED STATES PATENT OFFICE.

ALEXANDER GUENTHNER, OF WALSH, ALBERTA, CANADA.

PLOWSHARE.

1,410,403.

Specification of Letters Patent. Patented Mar. 21, 1922.

Application filed July 28, 1919. Serial No. 313,854.

To all whom it may concern:

Be it known that I, ALEXANDER GUENTHNER, of the village of Walsh, in the Province of Alberta, Canada, have invented certain new and useful Improvements in Plowshares, of which the following is a specification.

My invention relates to improvements in plowshares and the object of the invention 10 is to devise means whereby the share and share landside may be detachably connected to the frog formed integral with the mold board and landside plate also formed integral with the mold board and it consists 15 essentially of the following arrangement and construction of parts as hereinafter more particularly explained.

Fig. 1 is a perspective view of a plowshare constructed in accordance with my invention.

Fig. 2 is a perspective view of the part shown in Fig. 1 tilted up so as to exhibit the under side and showing the share and share landside in a partially detached position.

Fig. 3 is a longitudinal section through the lower portion of Fig. 1.

Fig. 4 is a plan section on line $x-y$, Fig. 3.

In the drawings like characters of reference indicate the corresponding parts in each figure.

1 indicates the landside of a plowshare from which the mold board 2 extends. 3 indicates a frog which is formed integral 35 with the landside 1 and mold board 2. The landside 1 is provided with a landside plate 1^x the forward portion of which extends beneath the landside 1. The forward end of the landside 1 is in angular form.

40 1° is a dove-tailed groove which extends longitudinally of the frog 3 and through the portion of the landside 1 adjacent to the frog. 4^x indicates the share provided with a share-point 4. 4^1 is a dove-tailed rib extending longitudinally of the share 4^x and slidably fitting within the groove 1° . 4° indicates a share landside formed integral 45 with the share-point 4 and corresponds substantially in shape to the forward portion of the landside 1. The rearward end of the share landside 4° is provided with a longitudinal slot 4^2 terminating in a triangular orifice 4^3 . The landside plate 1^x is provided with a longitudinal slot 1^1 which is 55 in longitudinal alignment with the slot 4^2 .

5 indicates a locking member pivotally

mounted in the slot 1^1 by a cross pin 5². The forward end of the locking member 5 is provided with a triangular head 5³ adapted to fit the triangular orifice 4^3 formed in the share landside. 1² is a recess formed in the landside 1 and is provided with a groove extension 1³ in vertical alignment with the slot 1^1 . 1⁴ is an orifice which extends from the recess 1². 6 is a spiral spring 65 which fits within the orifice 1⁴ and bears at its opposite end against the opposing face of the triangular head 5³ so as to hold the locking member 5 in the horizontal position.

When it is desired to detach the share and share landside from the remaining portion of the plowshare, all that it is necessary to do is to turn the plowshare on its side and press an instrument against the triangular head 5³ of the locking member 5 so as to force it inward into the recess 1² against the pressure of the spring 6. When this is done the share landside may be grasped and drawn together with the share 4^x longitudinally of the frog 3 to carry the rib 4^1 out of engagement with the groove 1° thereby detaching the share 4^x from the frog 3.

It will also be noted that in drawing, the share as it moves longitudinally of the frog does not move in a direction directly at right angles to the face of the landside 1, but in an inclined direction so that under normal conditions when the share and share landside are locked by the locking member 5, 90 any tendency to move in this direction causes the triangular head 5³ to engage the orifice 4^3 and thereby prevent the movement of the share to disengage.

From this description it will be seen that 95 I have devised a very simple device whereby the share and share landside may be detachably connected to the frog and landside formed integral therewith and locked in position in such a way that the parts may 100 be easily unlocked and detached for the purpose of renewal.

What I claim as my invention is:

In a plowshare, the combination with the mold board, landside and frog formed integral and having a recess formed in the lower face of the landside, of a landside plate secured to the lower face of the landside and having an open ended slot in its forward end, a share and share landside formed integral 105 and adapted to extend beneath the aforesaid landside in alignment with the landside plate 110

and having a slot in longitudinal alignment with the slot of the landside plate and in vertical alignment with the recess of the landside and terminating in a triangular orifice, a locking bar pivoted intermediately of its length in the slot of the landside plate and provided with a triangular head fitting the aforesaid triangular orifice, a spring located within the frog and recess of the

landside and bearing against the triangular head of the locking bar, and a tongue and groove connection between the frog and share extending longitudinally thereof.

ALEXANDER GUENTHNER.
